UNITED STATES PATENT OFFICE.

JOHN ZILLIOX, OF BUFFALO, NEW YORK, ASSIGNOR OF ONE-HALF TO HARRY L. GREENE, OF ORCHARD PARK, NEW YORK.

FLUE-SCRAPER.

1,174,220.

Specification of Letters Patent.

Patented Mar. 7, 1916.

Application filed July 28, 1913. Serial No. 781,561.

To all whom it may concern:

Be it known that I, JOHN ZILLIOX, a citizen of the United States, residing at Buffalo, in the county of Erie and State of New York, have invented new and useful Improvements in Flue-Scrapers, of which the following is a specification.

This invention relates to a flue scraper or cleaner for removing the soot, dirt or incrustations from the inner sides of boiler tubes or flues and has the object to produce a strong and durable device of this character which is effective in operation, convenient of manipulation and capable of being produced at comparatively low cost.

In the accompanying drawings: Figure 1 is a side elevation of a flue scraper embodying my invention. Fig. 2 is a longitudinal section of the same. Fig. 3 is a front elevation thereof. Fig. 4 is a cross section thereof taken in line 4—4, Fig. 2, and looking forwardly. Fig. 5 is a plan view of the blank from which the head of the scraper is constructed.

Similar characters of reference indicate corresponding parts throughout the several views.

In its general construction this flue scraper comprises a head which is made up of the means whereby the flues are engaged for removing the soot or incrustations therefrom and the guiding devices whereby the entrance of the head into the flues is facilitated, and the means whereby this head is supported and operated.

In its preferred form the head of the flue scraper is made from a single sheet of spring steel or other suitable metal which is stamped out and bent to form a transverse hub 1 having a central opening 2, a plurality of scraping blades or cutters 3, preferably four in number, which project forwardly from the outer edge of the hub and a plurality of guide flanges 4 two of which are preferably arranged lengthwise at opposite longitudinal edges of each scraper blade and project inwardly therefrom. Each of the scraper blades is inclined so that the several blades together form a forwardly enlarging cone and each of the scraper blades is provided with a transverse cutting edge 5 at its front end and each blade narrows from its front end toward its rear end. Each of the longitudinal guide flanges is provided at its front end with an inclined

guide face 6 which slopes from its rear end downwardly and inwardly toward its front end so that the guide faces of the several guide flanges together form a cone which reduces forwardly. Although various means may be employed for supporting this scraper head while in use those shown in the drawings are suitable and comprise a coupling bolt 7 having its shank arranged in the opening of the hub 1 while its head 8 bears against the front side of the hub, a retaining cap having a perforated bottom 9 which receives the shank of the coupling bolt and bears against the rear side of the hub and an annular forwardly projecting flange 10 which engages with the outer sides of the scraper blades at the rear ends thereof, and a clamping sleeve 11 bearing at its front end against the rear end of the cap and having an internal screw thread which engages with the externally threaded rear end of the coupling bolt. This clamping sleeve also serves as a means for coupling the scraper with a rod or tube 12 of any desired length whereby the scraper is moved back and forth in the tube or flue of the boiler which is to be cleaned.

When inserting the scraper into a boiler tube or flue the inclined guide faces of its guide flanges engage with the front end of the tube and serve to guide the scraper into the tube, thereby facilitating this operation. If the tube to be cleaned is smaller than the normal diameter of the front ends of the scraper blades the latter upon being pushed into the flue or tube are contracted the required extent for this purpose which is permitted by reason of the flexible connection between the front ends of the several scraper blades and the hub of the scraper head.

By reason of the guide flanges being arranged lengthwise at the longitudinal edges of the scraper blades the latter are materially strengthened or stiffened so that the same are very strong and durable and not liable to be bent out of shape by hard usage. By engaging the retaining cap with the outer sides of the scraper blades in front of the rear ends thereof outward deflection of the scraper blades is prevented and the several blades are always held in their normal operative position. By making the several blades and guide flanges and the hub of the scraper head all in one piece from a single sheet of metal the construc-

tion of the scraper is materially simplified, there is little liability of any parts getting out of order and it also permits of producing the scraper at very low cost.

5 I claim as my invention:

1. A flue scraper comprising a head constructed of a single sheet of metal having a central hub, a plurality of scraper blades projecting at an angle from the outer edge 10 of the hub and forming together a cone which enlarges forwardly and each blade having a transverse cutting edge at its outer end, and a plurality of longitudinal guide flanges projecting inwardly from opposite 15 longitudinal edges of each cutter blade and each guide flange having an inclined guide face at its outer edge, the guide faces of the several flanges together forming a cone which reduces forwardly.
- 20 2. A flue scraper comprising a head constructed of a single sheet of metal having a central hub, a plurality of scraper blades projecting at an angle from the outer edge of the hub and forming together a cone 25 which enlarges forwardly and each blade having a transverse cutting edge at its outer end, and a plurality of longitudinal guide flanges projecting inwardly from opposite longitudinal edges of each cutter blade and 30 each guide flange having an inclined guide face at its outer edge, the guide faces of the several flanges together forming a cone which reduces forwardly and supporting 35 means for said head comprising a coupling belt arranged with its shank in an opening

formed in said hub and having a head at its front end which engages with the front side of said hub, a retaining cap having a bottom engaging with the rear side of said hub, a central perforation which receives 40 the shank of said bolt and a marginal forwardly projecting flange which engages with the outer sides of the scraper blades at the rear ends thereof, and a screw sleeve 45 engaging with the threaded rear end of said coupling bolt and bearing against the rear side of said cap.

3. A flue scraper comprising a longitudinal 50 scraper blade having a transverse cutting edge at its front end, and a longitudinal guide flange projecting inwardly from a longitudinal edge of the cutter blade and having an inclined guide face at its front end.

4. A flue scraper comprising an integral 55 hub, a plurality of scraper blades projecting forwardly from said hub and integral therewith and each having a radial guide flange on a longitudinal edge thereof and a support on which said hub is mounted and 60 which is provided with retaining means engaging with the outer sides of said blades at the rear ends thereof.

Witness my hand this 7th day of July, 1913.

JOHN ZILLIOX
